UNITED STATES PATENT OFFICE.

JACOB MILLER, OF CANTON, OHIO.

HARVESTER-FRAME.

SPECIFICATION forming part of Letters Patent No. 393,383, dated November 27, 1888.

Application filed August 22, 1887. Serial No. 247,558. (No model.)

To all whom it may concern:

Be it known that I, JACOB MILLER, a citizen of the United States, and a resident of Canton, county of Stark, State of Ohio, have 5 invented a new and useful Improvement in Harvester-Frames, of which the following is a full, clear, and exact description, reference being had to the accompanying drawings, making part of this specification.

10 My invention relates to improvements in harvester-frames; and it consists in providing a metal-pipe frame of the form substantially as shown and hereinafter described.

15 My invention also relates to the detail and combination of parts, as set forth in the claims.

Figure 1 is a plan view of a harvester-frame embodying my invention. Fig. 2 is an isometrical perspective view from the rear. Fig. 3 20 is a view in perspective of a bracket-support for the harvester platform-frame, the said bracket being turned partially around and over to more clearly show its construction. Fig. 4 is a view in perspective of the rear journal-box 25 for crank-shaft and pipe-coupler; Fig. 5, a rear elevation of the harvester; and Figs. 6 and 7, a modification of bracket in Fig. 3, showing the same in side and end elevation.

Similar letters of reference indicate corresponding parts in all of the figures of the drawings.

Letter A represents the front and B the rear sills, C the outside sills, and D the inside sills. The ends of the sills have a screw-thread 35 adapted to a similar screw-thread in the corner-irons or elbows E. The said elbows are also provided with an upwardly-projected angle-flange, a, adapted to support the frame-pieces F, which are secured to the flange by 40 the bolts a' through perforations a'', the frame-piece F at the front and rear of the elevator-frame extending upwardly from the outer sill, C, and curved over transversely on the machine to positions inside of the inner sill, D, to 45 form supports for the elevator and the binding mechanism. Their location and general shape are clearly shown in Fig. 5. There is also provided on said elbows a downwardly-projected lug, a'', adapted to support the truss 50 G, the lower ends of which are provided with screw-threads and a threaded nut, a'', by

which the said truss-cord may be adjusted over the segment H. The said segment is made of suitable cast metal, and is provided at its upper end with a groove, a'', or other suitable means to secure the truss-cord to the segment, and is also provided with a flanged portion, a'', semicircular in cross-section, adapted to fit the outside sill, C, by which the segment is secured to the sill by the through-bolts a'.

As a support for the rear end of inside sill, D, and crank-shaft I, a hanger, J, is provided, having a neck portion, b, provided with a female screw adapted to the screw-thread on the 65 inside sill, D, and a body portion, b', having an annular bore, b'', adapted to fit the sill B, and a downwardly-projected neck portion, b'', a journal-box, b'', integral therewith, for the rear end of crank-shaft I, and a downwardly-projected lug, b'', (see Fig. 1,) similar to a'', on the elbow E, through which the end of the inner truss-cord is passed and secured by a threaded nut in the same way as the outer one. The front end of said sill is supported by a coupler, K, having an inwardly-projected portion, b'', provided with a female screw adapted to the screw-thread on the end of the inside sill, D, and body portion b'', the annular bore of which is adapted to the circumference of the front sill, A. The said coupler is also provided with a downwardly-projected lug, f, similar to that shown at a'' on elbows E, for the support of the front end of the inner truss-rod, G. There is also provided, and integral with said coupler K, an upwardly-projected lug, b'', having a perforation for the tongue-bolt b''. 75

The front end of the crank-shaft I is supported by a hanger, L, the upper end of 90 which is provided with a body portion, d, semicircular in cross-section and adapted to the circumference of the inside sill, D, and the through-bolts d'' secure the hanger to the girder. In the lower portion of the said 95 hanger there is provided a journal-box, d'', for the front end of the crank-shaft I and an outwardly-projected lug, d'', forming a support for the inner end of the finger-bar M.

The tongue support and brace N is formed 100 substantially as shown, the rear end, d'', being connected to the bar M by bolt d''. The mid-

dle portion of the brace N is provided with a laterally-projected flange and lug, d^6 , by which the brace is secured to the sill by a bolt, d^4 , as shown. There is also provided an upwardly-projected lug, d^7 , having a perforation for the tongue-bolt b^8 , as shown. A brace, X, is provided, having one of its ends secured to the inner segment H, the other end to the finger-bar M. The inner segment H is constructed and secured to its sill in a manner quite similar to that of the outer segment H, hereinbefore referred to, the half-sleeve a^6 in the latter being considered the essential equivalent of the flanged portion a^6 of the former.

15 The shoe O, which is preferably made of malleable cast-iron, has on its upwardly-projected front portion shoulders h^1 , semicircular in cross section, adapted to the circumference of the sill A. The rear portion of the said shoe is provided with shoulders h^2 and flanges h^3 , adapted to the angle h^5 of the bar M and a rearwardly-projected lug, h^6 , and is secured to the said bar by bolts through the shoulders h^2 and lug h^6 .

25 Plate P is provided as a support for the inner end of sill B and the rear frame-bar, Q, of the harvester-platform, the said plate having shoulders h^7 , semicircular in cross-section and adapted to fit the rear sill, B, a horizontal body portion, h^8 , and a downwardly-projected flange, h^9 , having outwardly-projected ribs h^{10} . These parts are adapted to embrace and support the platform rear bar, Q. There is also provided, and integral with said plate, a journal box, h^1 , for the shaft h^1 of the platform-canvas roller h^5 . (See Fig. 1.) The inner end of the platform-bar Q is bent up (see Figs. 2 and 5) and bolted to a hanger, R, bolted to the inside sill, D.

30 The inner end of sill A is connected to the upper front portion of the shoe O, and the finger-bar M connected to and supported by the lower rear portion of the said shoe, the inner end being extended to and supported by the inside sill, D, through the hanger L, and the inner end of sill B is connected to the upper rear portion of the plate P, the frame-bar Q being connected to the lower front portion of said plate, the inner end extended to 45 and supported by the inner sill through the hanger R; but, if preferred, the ends of the bars M and Q may be directly connected to the inside sill, D. By this feature of overlapping and bracing of the sills A and B and the bars M and Q a rigid connection is formed between the platform and machinery supporting frames; or, if preferred, the rear bar, Q, may be made of pipe, as T, (see Figs. 6 and 7,) the same as sill B, and the two connected, as 50 shown in Fig. 6, by a depending bracket, S, having an upper portion, h^2 , semicircular in cross-section, adapted to fit the sill B, to which it is bolted, as shown, a web portion, j^1 , and a cylindrical portion, h^1 , having an annular bore adapted to the circumference of the pipe-bar T, into which the bar may be passed and secured by the bolts h^3 . The bottom

board, h^5 , has a transverse groove, h^6 , and is bolted to bar T, as shown.

55 h^7 is a bar forming bearings for the platform-conveyer rollers, and h^8 a fastening for this bar.

The stud-axle U is of the form substantially as shown, the U-shaped frame-piece V, supported by adjustable supports j^1 on the outside and inside sills, C and D, forming a support for the shaft W and turned back on itself, forming the stud-axle U, as shown, which supports the pinion m and wheel n .

Having thus fully described the nature and object of my invention, what I claim, and desire to secure by Letters Patent, is—

1. The combination, with the sills A, B, and C of the rectangular harvester-frame, of elbows E, each having an upwardly-projected angle-flange, a^1 , the pieces F, set upon the elbows and secured to the flanges, downwardly-projected lugs a^2 on the elbows, and the truss-rod G, secured at either end in the lugs a^2 , substantially as set forth. 90

2. The combination, with the sills A, B, and C of a rectangular harvester-frame, of elbows E, each having a downwardly-projected lug, a^3 , to receive either end of the truss-rod G, truss-rod G, and the segment H, as a support for the 95 truss-rod G, said segment having a flange portion semicircular in cross-section to fit the outside sill, C, by which the segment is secured to the sill, substantially as set forth.

3. The combination, in a metal-pipe harvester-frame, of the front and rear pipe sills, A and B, the pipe inside sill, D, and the coupler J, having a neck portion, b^1 , a body portion, b^2 , a downwardly-projected neck, b^3 , a journal-box integral therewith, the shaft I, supported 100 in the journal-box, the coupler K, with its downwardly-projected lug as a support for the front end of the truss-rod, a truss-support, b^4 , and the truss-rod, the rear end secured therein, substantially as set forth. 110

4. The combination, in a metal-pipe harvester-frame, of the front and rear pipe sills, A, B, the pipe inside sill, D, the truss, the tongue-bolt, and the coupler K, having a neck portion, b^1 , a body portion, b^2 , lug b^3 , and truss-supporting lug b^4 on the coupler J, substantially as described, and for the purpose set forth. 115

5. In a harvester-frame, the combination, with the inner sill, D, the crank-shaft I, and finger-bar M, of the hanger L, secured to said sill and having therein a journal-box, d^2 , for the crank-shaft I and a downwardly-projecting flange, d^3 , as a support for the inner end of the finger-bar M, substantially as set forth. 120

6. In a metal-pipe harvester-frame, the tongue support and brace N, rigidly secured to the sill A, having an upwardly-projected lug, d^4 , having a perforation therethrough to receive the tongue-bolt, and a tongue-bolt, b^5 , the rear end of said brace projecting rearwardly, as shown, and rigidly secured to the finger-bar M, substantially as set forth. 130

7. The combination of the sill A, shoe O,

and finger-bar M, said shoe having shoulders h , semicircular in cross-section, shoulders h^2 , and flanges h^4 , adapted to the angle h^5 of the finger-bar M, substantially as described.

5 8. In a harvester-frame, the sill A, shoe O, finger-bar M, hanger L, and inside sill, D, the bar M connected to the hanger, and all combined and operated as shown and described, and for the purpose set forth.

10 9. In a metal-pipe harvester-frame, the combination of the sill B, bracket S, having its upper portion, h^2 , secured to the sill B, a downwardly-projected web portion, j , and a cylinder portion adapted to embrace the end 15 of the frame-bar T, and in which the said bar may be secured, substantially as described, and for the purpose set forth.

10 10. In a harvester-frame, the combination of the sill D, truss-rod G, segment H, brace X, 20 and finger-bar M, the segment H forming a connection between the truss-rod and sill, and the brace X connecting the segment and finger-bar, the truss G being further connected to the sill D at its ends by suitable coupling devices.

25 11. The U-shaped frame-piece V, supported on the outside and inside sills, C D, and form-

ing a support for the shaft W, the free end of said frame-piece being turned back on itself, forming the stud-axle U, for the purpose substantially as shown and described, and for the 30 purpose set forth.

12. The combination, in a harvester-frame, of the pipe-frame bar T, bottom boards, h^5 , having transverse grooves h^6 , bracket h^8 , roller-bearer h^7 , and bracket S, substantially as set 35 forth.

13. In a harvester, the adjustable U-shaped frame-piece V, supported on the outside and inside sills on the supporting-frame, substantially as shown, as a support for the shaft W 40 and the gear-wheels m and n , and having the stud-axle U at the end of the U-shaped portion of the said frame-piece, and means for adjusting the said frame-piece, substantially as set forth.

In testimony whereof I have hereunto set my hand this 13th day of August, A. D. 1887.

JACOB MILLER.
